UNITED STATES PATENT OFFICE.

MARY E. SANBORN, OF NEW YORK, N. Y.

GARMENT.

Application filed March 28, 1923. Serial No. 628,190.

To all whom it may concern:

Be it known that I, MARY E. SANBORN, a citizen of the United States, residing at New York, county and State of New York, 5 have invented certain new and useful Improvements in Garments, of which the following is a specification.

This invention relates to service or protective garments, such as used by various 10 tradesmen, personal attendants, and professional persons, or as a garment for wear in doing household and similar work.

The object of the invention is to provide a garment of the nature referred to 15 which has a detachable front or apron-like portion of simple shape and form, easily cleaned or laundered, which receives the greater part of the soiling and discolorations incidental to the tasks of the wearer, 20 and which may be replaced from time to time by a clean front or apron-like portion, or cleaned, and thereby considerably lengthen the time the garment may be worn before becoming unsightly or unattractive 25 in appearance.

A further object is to provide a garment such as described which is of attractive appearance, simple construction, and well adapted for laundering.

30 An embodiment of the invention is illustrated in the accompanying drawing, in which—

Figure 1 is a front view of the garment, and

35 Figure 2 is a detail view of a button strip forming a part of the garment.

Referring to said drawings, numeral 10 designates a coat, jacket, or dress of any 40 convenient form, usually made of white or other light colored material, which readily shows dirt and discolorations, so that a soiled condition of the garment is readily detected, and which may be replaced by a clean garment, to present a more sanitary and attractive appearance. This garment may be open in the front, as indicated at 12, and closed by buttons and button-holes 13.

15 designates a front or apron-like portion, of simple form, such as a simple flat rectangular piece of material (rubber-sheeting, cloth, etc.), adapted to be detachably fastened to the front of the garment 10.

For fastening the apron-like portion 15 55 to the garment 10, the garment is provided on each side of its front with two rows 17

and 18 of buttons or other similar fastening devices 20, a plurality of buttons 20 being preferably provided in each row 17 and 18, one set 23 being preferably provided at 60 the chest-level and another set 24 at the waist level, and the apron-like portion is provided with button-holes or the like 25, 26 for detachably fastening on said buttons 20. The button-holes 25 are conveniently adapted to fasten on one or another of the buttons 20 in the set 23, and the button-holes 26, on one or another of the buttons 20 of the set 24, and by fastening the button-holes 25, 26 on buttons at a 70 greater or less height in the series 17, 18, the height of the apron-like portion 15 on the wearer, may be adjusted.

The buttons 20 are conveniently fastened on strips 30 detachably arranged on the inner side of the garment, and the buttons fastened to the garment 10 by passing through a plurality of button-holes 31 in said garment. The strip 30 preferably has an upwardly extending portion 33 which is 75 adapted to be fastened to the shoulder portion of the garment as by means of a button 35 and button-hole 36, said portion 33 thereby acting as a suspender for the buttons 20, and thereby as a suspender for the 80 apron-like portion 15.

When the apron-like portion 15 becomes soiled it may be readily removed, by unfastening the buttons and button-holes 20, 25, 26 and cleaned, or replaced by a fresh 90 laundered similar apron-like portion 15. When it is desired to wash and launder the garment 10, this may be readily done after removing the button-strips 30.

The apron-like portion 15 may have extensions around the waist, or be otherwise shaped to cover desired parts of the garment 10.

While the embodiment chosen for illustration is the preferred form of the invention, modifications thereof may be made without departing from the spirit of the invention. For instance, the button strip may also be made to extend over the shoulder and down the back portion of the garment so that the apron may be secured to the back of the garment as well as the front. The strip may also be provided with side extensions so that the apron may be secured to the side of the garment if desired. 100 105 110

What is claimed is—
1. The combination of a garment com-

prising a body portion having a plurality of longitudinally spaced openings toward each side of the front thereof, a longitudinally disposed strip toward each side beneath said openings, fastening devices carried by said strips and extending through said openings, and a detachable front for said garment having fastening devices toward each side thereof spaced correspondingly to the first mentioned fastening devices for cooperation therewith to permit said detachable front to be removably secured in a plurality of adjusted positions.

2. The combination of a garment of the class described, of a detachable front or apron-like portion having means for ad-

justably securing the same to said garment, said means comprising a longitudinally disposed strip on the inside adjacent each edge of the front portion of said garment, a plurality of groups of buttons on each strip extending through said garment, the buttons of each group being spaced corresponding to the buttons of the next group, and button holes in said apron-like portion for receiving said buttons for adjustably securing the apron-like portion in a number of longitudinally adjusted positions.

In testimony whereof, I have signed my name to this specification this 27th day of March 1928.

MARY E. SANBORN.
